Douglas Lorie, Palm Beach, Fla.

Application February 24, 1953, Serial No. 23,754

Term of patent 3½ years

(Cl. D33—1)

To all whom it may concern:

Be it known that I, Douglas Lorie, a citizen of the United States, residing at Palm Beach, State of Florida, have invented a new, original, and ornamental Design for a Letter Box, of which the following is a specification, reference being had to the accompanying drawing, forming a part hereof.

Fig. 1 is a top plan view of a letter box, showing my new design;

Fig. 2 is a front elevational view thereof.

Fig. 3 is a rear elevational view thereof on a reduced scale.

I claim:
The ornamental design for a letter box, as shown.
